Primary Examiner — Doris Clark*(74) Attorney, Agent, or Firm* — George G. Waggett, P.C.(57) **CLAIM**

I claim the ornamental design for a baluster end piece, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a front perspective view of my new design for a baluster end piece.

FIG. 2 is a back side view of FIG. 1. The front side view is a mirror image of the back side view.

FIG. 3 is a right side view of FIG. 2.

FIG. 4 is a left side view of FIG. 2.

FIG. 5 is a top end view of FIG. 2.

FIG. 6 is a bottom end view of FIG. 2; and,

FIG. 7 is a back view of FIG. 1.

The broken lines are for illustrative purposes only and form no part of the claimed design.
